PAGE 2

Fig. 3

Fig. 4

FIGURE 1 is a front elevational view of an assembly work rack embodying my new design.

FIGURE 2 is a rear elevation view thereof.

FIGURE 3 is a right side elevation view thereof.

FIGURE 4 is a left side elevation view thereof.

FIGURE 5 is a perspective view of the rack of FIGURE 1 with the upper portion thereof pivoted 90° on its base, and with the lower pivoting arms in different articulated positions.

I claim:

The ornamental design for an assembly work rack, substantially as shown.
